MAGNETRON

Ernest C. Okress, Montclair, N. J., assignor to
Westinghouse Electric Corporation, East Pittsburgh,
Pa., a corporation of Pennsylvania

Application July 1, 1943, Serial No. 492,995

11 Claims. (Cl. 315—6)

1

This invention relates to magnetrons and particularly to such devices in the ultra high frequency or so-called micro-wave range which, though not definitely defined, may be considered as certainly including wave-lengths up to one hundred centimeters.

Magnetrons as heretofore constructed have had a generally symmetrical arrangement of cavities, of which examples may be seen in my prior application, Serial No. 460,376, filed October 1, 1942, entitled Magnetron and method of manufacture, and assigned to the same assignee as the present application. The prior art, in its relation to the invention here disclosed, may be summarized as providing a generally cylindrical central cavity for the cathode, and having a plurality of radiating cavities evenly spaced around and opening into the central cavity. An even number of radiating cavities constitute the multiplicity thereof used, and in quantity usually range from six to ten with eight radiating cavities most commonly employed. This prior art type of magnetron has serious disadvantages amongst which may be mentioned the difficulty in fabrication of obtaining the requisite accuracy which has to be in some instances within ± 0.0005 of an inch. Manufacture is consequently expensive and involves many discarded magnetrons due to discrepancy from the permitted tolerance. It has also been found that the multi-cavity magnetrons of the prior art promote oscillation or resonance in a plurality of modes rather than just a desired single mode. Strapping of alternate anode segments has been resorted to in the prior art in an effort to overcome this undesirable behavior, but not with complete success, and in addition added electrical and mechanical difficulties are introduced.

The present invention has for its general object the purpose of presenting another means whereby such difficulties and deficiencies encountered in prior art magnetrons may be alleviated.

More specifically, an object of the invention is to overcome construction and operation productive of undesired modes of oscillation.

Another object of the invention is to simplify construction both to lessen the difficulty of satisfactory manufacture and cost and to reduce percentage of discards.

A further object of the invention is to enable the size of the magnetron for a given wave-length to be less than heretofore.

Again, an object of the invention is to provide a construction admitting of less critical tolerances without materially affecting operation.

2

Still further objects will appear as the description proceeds, both by direct recitation thereof and by implication from the context.

Referring to the accompanying drawing in which like numerals of reference indicate similar parts throughout the several views;

Figure 1 is a cross-sectional view, normal to the axes of the several cavities, of a magnetron constructed in accordance with my invention, as upon line I—I of Fig. 2;

Figure 2 is a vertical section on a plane defined by the axes of the cathode cavity and of the input and output leads;

Figure 3 is a sectional view as on arcuate line III—III of Fig. 1 for purposes of showing graphically the magnetic field lines of force in the resonant cavities;

Figure 4 is a diagrammatic view similar in nature to Fig. 1 but graphically showing the E and H lines theoretically present in the cavities;

Figure 5 is a vertical sectional view similar to Fig. 2 and showing a construction modified as to output lead, the section being taken on a plane indicated by line V—V of Fig. 6;

Figure 6 is a cross-sectional view on line VI—VI of Fig. 5;

Figure 7 is a cross-sectional view corresponding to structure generally of Figures 1 to 4 except for modification of the form of cavity resonators;

Figure 8 is a cross-sectional view corresponding to Fig. 6 but modified as to the number of cavity resonators;

Figure 9 is a section on line IX—IX of Fig. 8, and

Figure 10 is a cross-sectional view corresponding to Fig. 8 but modified as to character of cavity resonators and output coupling.

In the specific embodiment of the invention illustrated in said drawing and directing attention particularly to Figures 1 to 6 thereof, the reference numeral 15 designates a cylindrical magnetron body having end plates or covers 16 sealed thereto whereby the interior may be evacuated. The interior of said body is formed to comprise an anode 17 of generally cylindrical shape, shorter than the body which has end flanges 18 for spacing the covers 16 from the ends of the anode and thereby afford the usual and necessary end spaces 19 within the magnetron.

The present showing of the magnetron preferably provides a cathode cavity 20 parallel to but offset from or eccentric with respect to the axis of the anode body and magnetron, said cavity extending through the anode so as to open into both end spaces 19. Likewise eccentric to the

anode axis and extending longitudinally through the anode to the end spaces 19 are a plurality of resonant cavities 21 which are otherwise separate from each other but open longitudinally at the side of the cathode cavity 20 as by constriction 22 and constitute cavity resonators. In Figures 1 to 6, two cavity resonators 21 are shown of generally cylindrical shape and with distinct slot-like constrictions 22 interposed between the cylindrical part of the cavities 21 and the cathode cavity 20. In Figure 7, two cavity resonators 21a are shown of slot-like formation and in continuation of the slot-like constrictions 22a to the cylindrical cathode cavity 20a and all within an anode 17a of a magnetron otherwise substantially as described above. These two exemplifications illustrate the feature of eccentricity of cathode cavities in an anode and with two cavity resonators opening at the side thereof.

The feature of eccentricity of cathode cavity to the anode axis, however, is not confined to use of only two cavity resonators, and accordingly in Figures 8 and 9 a magnetron of the general form of Figures 1 to 6 is shown providing three cylindrical cavity resonators 21b each connected by a distinct slot-like constriction 22b to the cathode cavity 20b and all within an anode 17b of a magnetron otherwise substantially as described above. And, furthermore, the feature of eccentricity with a plurality, more than two, of slot-like cavity resonators may be employed and is exemplified in Figure 10, wherein three slot-like resonant cavities 21c are shown, the side walls of which are in continuation of the slot-like constrictions 22c to the cylindrical cathode cavity 20c shown eccentrically situated in an anode 17c of a magnetron otherwise substantially as described above.

Consequently, in all forms of the invention shown, the cathode cavity is eccentric to and at one side of the axis of the anode body and the cavity resonators are at an opposite side of the axis and a constriction lengthwise of the cavities connects each cavity resonator with the cathode cavity. Also in all forms of the invention, the ends of all cavities open into end spaces in the magnetron body.

Other structures common to all forms of the invention, and accordingly identified throughout by the same reference numerals, comprises a cathode 23 extending through the cathode cavity coaxial therewith and into the end spaces of the illustrated magnetron. The cathode is supported at its ends by ceramic or other insulating collars 24 on the outer ends of which are mounted metal discs 25 to which lead-in wires 26 are radially attached. These lead-in wires are sealed through appropriate sealing means 27 for the purpose at the side of the magnetron. A heater filament 28 extends through the cathode and is attached at its ends to said discs 25.

An output connection is made appropriately from within the magnetron. In constructions having an even number of cavity resonators, the output may conveniently be situated in an end space with symmetrical disposition of the cavity resonators on opposite sides of the output. In this instance, as shown in Figures 1 and 2, the output 29 is a wire, the end of which is embedded in the partition between two cavity resonators and next the cathode cavity, said wire at its embedded end portion being parallel to the axis of the cathode cavity and projecting away from the end of the anode into the end space where it bends at right angles and extends through the end

space medially across said partition and out through the side wall of the magnetron through appropriate sealing means 30. It is, however, within the scope of the invention to otherwise situate and construct the output lead. For instance, as shown in Figures 5 and 6, the output lead 31 is introduced midway of the length of one cavity resonator 21 and in the form of a loop, the plane of which is transverse to the cavity axis. With use of an odd number of cavity resonators, it is convenient to situate the output lead in a middle one of the several cavities. For instance, in the showing of Figures 8 and 9, there are three cylindrical cavity resonators, and a looped output lead 31 as above described may also be used here and inserted in the middle one of the three cavities. In Figure 10 showing three slot-type cavity resonators, the output 32 may conveniently have the form of a probe entering the middle one of said slot cavities perpendicular thereto.

With magnetrons as here disclosed in which more than two cavity resonators are employed, it is preferable to strap alternate partitions to each other, and by way of illustration staple-like straps 33 made of wire are shown in Figures 8 and 9.

The field conditions existing in the cavity resonators are indicated in Fig. 4 wherein are shown E lines representative of the electric component of the electromagnetic field and circles representative of the H or magnetic component of the electromagnetic field. The direction of the flux-lines H is indicated by the usual dot and cross within the circles, the dot indicating direction toward the reader and the cross indicating direction away from the reader. Conduction and displacement currents flow in accordance with Maxwell's theory, for the boundary conditions imposed as indicated in Figure 4.

Field conditions in the solid angle, α (see Fig. 4), are similar to those existing in the symmetric form. The D. C. fields required are higher, especially the cut off voltage. Both may be compensated by altering both the cathode and anode radius particularly by reducing the latter. The dimensions of the resonator system do not materially depart from the relations for the multiple cavity magnetron.

The dual cavity device operates on the buncher-catcher principle. External coupling should be made in the cavity which acts as a catcher as determined by the axial magnetic field polarity. A three cavity system should operate equally well with either direction of the axial magnetic field with the coupling device in the cavity as shown in Figure 8. Cross strapping as shown in this figure will improve the efficiency of operation in the fundamental mode.

It is a fact that a magnetron constructed in accordance with the present invention utilizing eccentric disposition of cavities and limited number of resonant cavities may be made much smaller than the prior art conventional symmetrical magnetron. The reduced number of cavities also reduces manufacturing operations and cost, and it has been advantageously ascertained that tolerances of dimensions are less critical. Of importance, likewise, is the fact that the magnetron constructed according to my invention tends to eliminate undesired modes and to inherently be confined to practically a single mode of wave propagation.

I claim:

1. A magnetron having an anode body substantially cylindrical about an axis, said body

having cavities therein longitudinally parallel to each other and to said axis, said body completely surrounding said cavities, one cavity of said cavities being axially offset from the said axis of the body and all other of said cavities radiating from the said one cavity, and a cathode in said one cavity.

2. A magnetron having an anode body substantially cylindrical about an axis, said body having cavities therein longitudinally parallel to each other and to said axis, said body completely surrounding said cavities, one of said cavities being cylindrical and axially offset from the said axis of the body and constituting a cathode cavity, and all other of said cavities each radiating from the said cathode cavity, and a cathode in said one cavity.

3. A magnetron having an anode body substantially cylindrical about an axis, said body having cavities therein longitudinally parallel to each other and to said axis, said body completely surrounding said cavities, one of said cavities being cylindrical and axially offset from the said axis of the body and constituting a cathode cavity and all other of said cavities constituting cavity resonators and each radiating from the said cathode cavity and having a width perpendicular to direction of radiation less than the diameter of said cathode cavity, and a cathode in said cathode cavity.

4. A magnetron having an anode body with a cathode cavity eccentrically disposed therein on one side of the middle of said body, and with cavity resonators eccentric to the anode body on an opposite side of the middle thereof and radiating from the cathode cavity, and a cathode in said cathode cavity.

5. A magnetron having an anode body with a cathode cavity eccentrically disposed therein on one side of the middle of said body, and dual cavity resonators eccentric to the anode body and both on an opposite side of the middle thereof and radiating from the cathode cavity, and a cathode in said cathode cavity.

6. A magnetron having an anode body with a cathode cavity eccentrically disposed therein on one side of the middle of said body, and more than two cavity resonators eccentric to the anode body, all of said cavity resonators being on an opposite side of the middle of the anode body and radiating from the cathode cavity, and a cathode in said cathode cavity.

7. A magnetron having an anode body with a cathode cavity eccentrically disposed therein on one side of the middle of said body, and an odd number more than two of cavity resonators eccentric to the anode body, all of said cavity resonators being on an opposite side of the middle of

the anode body and radiating from the cathode cavity, and a cathode in said cathode cavity.

8. A magnetron having an anode body with a cathode cavity eccentrically disposed therein and with an odd number only of evenly spaced cavity resonators radiating from thereby providing one radiating cavity resonator symmetrically between other radiating cavity resonators, and an output lead partially in and extending from said one radiating cavity resonator symmetrically between other radiating cavity resonators.

9. A magnetron having an anode body with a cathode cavity eccentrically disposed therein entirely on one side of the middle of said body, and said body having only two cavity resonators of diverging slot formation radiating from said cathode cavity on an opposite side of the middle of said body.

10. A magnetron having an anode body with a cathode cavity eccentrically disposed therein entirely on one side of the middle of said body, said body having an odd number only of cylindrical cavity resonators on the opposite side of the middle of said body from the said cathode cavity, and said cylindrical cavity resonators each having a slot connection with the cathode cavity.

11. A magnetron having an anode body with a cathode cavity eccentrically disposed therein entirely on one side of the middle of said body, said body having a total of only three slotlike cavity resonators radiating from said cathode cavity, and a probe-like output lead partially within and protruding laterally from the middle one of said cavity resonators.
